UNITED STATES PATENT OFFICE.

FRANK H. HAMPTON, OF PULLMAN, ILLINOIS, AND GUSTAVE A. FRANZ AND WATSON R. SMITH, OF JACKSON, MICHIGAN, ASSIGNORS TO JACKSON CUSHION EDGE COMPANY, OF JACKSON, MICHIGAN.

UPHOLSTERING DEVICE.

No. 916,700.

Specification of Letters Patent.

Patented March 30, 1909.

Application filed April 4, 1908. Serial No. 425,198.

To all whom it may concern:

Be it known that we, FRANK H. HAMPTON, GUSTAVE A. FRANZ, and WATSON R. SMITH, citizens of the United States, residing, FRANK H. HAMPTON at Pullman, county of Cook, State of Illinois, and GUSTAVE A. FRANZ and WATSON R. SMITH both at Jackson, county of Jackson, State of Michigan, have invented certain new and useful Improvements in 10 Upholstering Devices, of which the following is a specification.

This invention relates to upholstering devices.

In upholstering couches, lounges, and 15 similar articles, the edges of the upholstering material are usually rolled along their edges for the purpose of strengthening the same and particularly to provide for a proper shaping of the edges of the cushion. To 20 provide this roll edge pad or "roll edge", as they are sometimes called, there are different methods employed, the operations being usually accomplished by hand. In any event the methods practised are not altogether satisfactory, and they consume considerable time.

It is therefore one object of our invention to provide for an automatic filling or stuffing of a tubing or "edge-roll" of upholstering 30 material, and as the filling material is fed into and packed in the tubing or "edge-roll" the latter is gradually forced off its support so that the filling or stuffing and packing may continue evenly and continuously from the bottom until the tubing or 35 "edge-roll" is full.

Another object of the invention resides in the provision of a device embodying such characteristics that a canvas or other tubing 40 may be simultaneously stuffed and removed from the device in a single operation.

A still further object is to provide a device whose parts are organized under such conditions as to effectually perform the functions 45 of supporting a tubing of suitable material and supplying the same with a filler of hair, cotton, sawdust, felt or other suitable stuffing without a resultant bunching of the tubing incident to the filling operation and a simultaneous removal of the tubing during and at 50 the end of the filling process.

It is still further designed to provide a device capable of feeding the stuffing material continuously and evenly to the tubing and 55 pack it therein from the bottom until the

tubing is full, with means coöperating with the supporting means for the tubing to tension the tubing and thereby prevent bunching of the same.

With the above and other objects in view, 60 the present invention consists in the combination and arrangement of parts herein-after more fully described, illustrated in the accompanying drawings, and particularly pointed out in the appended claims, it being 65 understood that changes may be made in the form, proportion, size and minor details without departing from the spirit or sacrificing any of the advantages of the invention.

In the drawings:—Figure 1 is a longitudinal sectional view. Fig. 2 is a transverse sectional view. Fig. 3 is an end view. Fig. 4 is a view illustrating an edge-roll formed in accordance with our invention.

In the use of the present invention, it will 75 be understood that we provide for the formation of cushion edges on upholstered goods, such as car seats, automobiles, chairs, couches, box springs and the like. It will also be understood at the outset that the up- 80 holstering material with which the roll is stuffed is preferably fed automatically instead of by hand, and reference to the accompanying drawings will disclose that the de- 85 vice is mounted upon a composite base, there being a wood supporting base 1 and a metallic base 2 mounted over the wood base. However, the means for mounting the device is immaterial and it will be understood that the composite base may be eliminated and 90 that any other base for the support of the device may be employed.

Disposed upon the base intermediate its ends is a suitable frame consisting of pairs of spaced uprights 3 and 4, each pair connected 95 at its top by a sill 5. This frame is provided particularly for the support of the feed rolls 6 and 7, they being journaled upon suitable axes 8 and 9, respectively, the upper feed roller 6 being mounted in a slidably boxing 10 forced normally toward the axis 9 of the roller 7 through the instrumentality of a helical or other spring 11, whose tension may be 100 adjusted by means of the bolts 12 passed through the sills 5 and which are encircled by 105 said springs 11, as clearly shown in the drawings. Each feed roller 6 and 7 is provided with an annular groove 13 and 14, respectively, which grooves of the respective rollers are adapted to aline for the purpose of form- 110

ing an opening between them for the passage of the feed screw 15 hereinafter more particularly described.

To support the tubing or "edge-roll" 16 for stuffing there is provided an elongated supporting tube 17 whose interior is corrugated, as indicated at 18 for the purpose of insuring a positive feed of the filling material through the supporting tube, the corrugations 10 preventing the material from clinging to the inner walls of the tubing and insuring the material being fed through the tubing by the feed screw 15. The inner end of the supporting tubing 17 is flared and projects into 15 the aforesaid frame and into close proximity to the feed rollers 6 and 7, there being a radial flange 19 formed at the flaring end of the tubing 17 whereby the latter may be secured at its inner end to said frame through the 20 instrumentality of suitable fastening elements 20. The outer end of the tubing 17 is supported in a split sleeve 21, which split sleeve 21 is provided with oppositely disposed bosses 22 having screw threaded 25 sockets 23 for the reception of the inner ends of the screw bolts 24 passed through the standards 25 secured to the base. This split sleeve 21 has its split 26 extending longitudinally throughout its length and it is split 30 for the purpose of permitting transverse contraction and expansion of the sleeve upon operation of the bolts 24 so that the tubing or "edge-roll" 16 may be properly tensioned upon the supporting tube 17 to overcome the 35 possibility of bunching of the "edge-roll" material and a consequent lumping of the "edge roll" incident to the filling of the latter and the packing of the material therein and the removal of the "edge-roll" from its 40 supporting element 17.

The conveyer or feed screw 15 extends through the opening between feed rolls 6 and 7 into the supporting tube 17 and has its outer end journaled in a suitable bracket 27 45 secured to the base by means of suitable fastenings 28, there being a pulley 29 mounted upon the feed screw 15 adjacent the standard 27 to receive an operating belt 30 adapted to operate the feed screw when the sawdust, 50 felt, cotton, hair, or other suitable filling material is to be fed into the supporting tubing 17 by way of the feed rolls 6 and 7 from the hopper 31, there being an endless conveyer 32 provided with transverse ribs 33 mounted in 55 the hopper to agitate the material therein and particularly to carry the material in the hopper upwardly therein and then downwardly to the feed rollers 6 and 7, the lower roller having a preferably smooth periphery and 60 the upper roller being preferably corrugated to facilitate the carrying of the filling material between the rollers and into the tubing 17. The conveyer 32 is mounted at its upper end upon an axis 34 journaled through the 65 hopper 31, the axis 34 being provided with a

pulley 35 over which works a cord or other belt 36 which also works around a pulley 37 mounted upon the axis 8 of the upper feed roller 6, whereby, when the feed rollers are operated in a manner hereinafter explained, 70 the conveyer 32 will operate simultaneously therewith. To operate the feed rollers 6 and 7 there is disposed upon the axis 9 of the lower feed roller a beveled gear 38 adapted to mesh with a beveled gear 39 mounted upon 75 the axis 40 journaled in the standard 41 secured to the supporting base of the device. The axis 9 also carries a gear 42 adapted to mesh with a gear 43 carried by the axis 8 of the upper feed roller so that when the beveled gear 39 is driven it will convey motion to the gear 43 and consequently to the upper feed roller 6 through the instrumentality of the intermeshing gear 42 and beveled gear 38, as 80 will be well understood. The axis 40 of the 85 beveled gear 39 may be driven from any suitable source, but it is preferred to drive it simultaneously with the driving of the feed screw 15, through the instrumentality of a connecting belt or other suitable element 44, so that all of the operating elements of the device will operate simultaneously to automatically stuff the tubing, pack it, and remove the same in its stuffed and packed condition from the supporting tube 17. 95

In the use of the present invention, the tubing or roll edge is formed into substantially bag shape, that is the sides and one end being closed and the opposite end open. The roll edge or tubing thus formed is then 100 placed upon the holding tube 17 with the closed end at the outer end of the latter. The device is then set into operation and the filling material of the hopper passes between the feed rollers and into the supporting tube 105 17 through which it is worked to the outer end by means of the conveyer screw. As the filling material is conveyed to the outer end of the supporting tube and consequently to the closed end of the edge roll, it gradually 110 becomes stuffed or filled resulting in the tubing or edge-roll, incident to the packing and the filling or stuffing material therein, being forced gradually off of the tubular support 17 so that the filling or stuffing and packing 115 may continue evenly and continuously from the closed end of the edge-roll until the latter is full. As shown, the cross sectional view in Fig. 4 discloses an edge-roll prior to being filled, and also indicating one method of securing the sides of the edge-roll together. 120

What is claimed is:—

1. A device of the character described comprising a hollow tube for the support of the edge-roll, feed rollers mounted adjacent the inner end of the tube, each feed roller having an annular groove in its periphery to provide an opening between them, a feed screw mounted in the tube and working through the opening formed by said grooves 130

in the feed rollers, means for operating the screw, and a hopper mounted adjacent the feed rollers.

2. In a device of the character described, 5 a supporting tube for the edge-roll, a hopper, means between the hopper and the supporting tube to feed the filling material to the latter, a feed screw operable in the tube, yieldable means embracing the tube and the 10 edge-roll to prevent a lumpy packing of the latter during the filling of the edge-roll, and means whereby said yieldable means may be adjusted to regulate the tension upon the edge-roll during the operation of the device.
- 15 3. A device of the character described comprising a hollow corrugated tube having a flaring inner end and adapted for the support of the edge-roll, feed rollers mounted adjacent the flaring end of the tube, each 20 feed roller having an annular groove in its periphery to provide an opening between them, a feed screw mounted in the tube and working through the opening formed by said grooves in the feed rollers, means for 25 operating the screw, a hopper mounted adjacent the feed rollers, and a conveyer mounted in the hopper.

4. In a device of the character described, a corrugated tube having a flaring inner end, 30 feed rollers mounted adjacent the flaring end of said tube, a groove formed in the periphery of the feed rollers to provide an opening between them, a feed screw mounted in the tube and working through the opening be- 35 tween said rollers, means for operating the feed screw and feed rollers simultaneously, a hopper, a conveyer disposed in the hopper, a connection between the conveyer and one of said rollers to operate the former upon 40 operation of the latter, means yieldably embracing the roll and tubing, and means for tensioning the last mentioned means to prevent a lumpy packing of the roll during operation of the device.

- 45 5. In a device of the character described, a supporting tube for the edge-roll, a hopper, means between the hopper and the supporting tube to feed the filling material to the latter, a feed screw operable in the tube, and 50 yieldable means embracing the tube and the edge-roll to prevent a lumpy packing of the latter during the filling of the edge-roll.

6. In a device of the character described, a supporting tube for the edge-roll, the inner 55 surface of the supporting tube being corrugated, a hopper for the filling material, means for feeding the filling material from the hopper into said tube, and a feed screw to feed the material through said tube and 60 into the edge-roll, whereby the latter may be filled and packed and removed from the supporting tube.

7. In a device of the character described, a supporting tube for the edge-roll or canvas 65 tubing, the supporting tube being corrugated upon its interior, a hopper for the filling material, feeding rollers between the hopper and supporting tube, one of the rollers being corrugated and each roller being grooved to provide an opening between them, a feed screw working through the opening of the feed rollers and extending into the supporting tube to feed the filling material through the latter and into the edge-roll or 70 canvas tubing to fill the latter with the filling material.

8. In a device of the character described, a supporting tube for the edge-roll or canvas tubing, the supporting tube being corrugated upon its interior, a hopper for the 80 filling material, feeding rollers between the hopper and supporting tube, one of the rollers being corrugated and each roller being grooved to provide an opening between them, a feed screw working through 85 the opening of the feed rollers and extending into the supporting tube to feed the filling material through the latter and into the edge-roll or canvas tubing to fill the latter with the filling material, means for simultaneously operating the feed screw and feed 90 rollers, and means embracing the edge-roll or canvas tubing to prevent a lumpy packing of the latter during the operation of the device.

9. In a device of the character described, a supporting tube for the edge-roll or canvas tubing, the supporting tube being corrugated upon its interior, a hopper for the filling material, feeding rollers between the 100 hopper and supporting tube, one of the rollers being corrugated and each roller being grooved to provide an opening between them, a feed screw working through the opening of the feed rollers and extending into the 105 supporting tube to feed the filling material through the latter and into the edge-roll or canvas tubing to fill the latter with the filling material, a longitudinally split sleeve embracing the edge-roll or canvas tubing, the 110 split sleeve having bosses provided with screw threaded sockets, standards mounted upon opposite sides of the sleeve, and screw bolts working through the standards and entering the sockets of the corresponding bosses 115 of the sleeve whereby the latter may be contracted or expanded transversely to regulate the tension of the sleeve upon the edge-roll or canvas tubing.

10. In a device of the character described, 120 a supporting tubing for the edge-roll, a hopper for the filling material, means between the hopper and the supporting tubing to feed the filling material from the hopper to said tubing, means arranged in said tubing to 125 feed the filling material through the latter, a split sleeve embracing said tubing and the edge-roll, and means whereby the edges of the split tube may be adjusted toward and away from each other to regulate the tension 130

upon the edge-roll during the operation of the device.

11. In a device of the character described, a supporting tube for the support of the edge roll, the interior of the tube being corrugated, means disposed in the tube to feed the filling material through the tube, a sleeve embracing the edge roll and the tube, the sleeve being split longitudinally, and means whereby 10 the longitudinal edges of the split sleeve may be adjusted toward and away from each other to regulate the tension upon the edge-roll during the removal of the roll from its supporting tube during the filling and pack- 15 ing of the roll.

12. A device of the character described comprising a hollow tube having a flaring inner end and adapted for the support of the edge-roll, feed rollers mounted adjacent the 20 flaring end of the tube, each feed roller having an annular groove in its periphery to provide an opening between them, a feed screw mounted in the tube and working through the opening formed by said grooves in the 25 feed rollers, means for operating the screw, a hopper mounted adjacent the feed rollers, and a conveyer mounted in the hopper.

13. A device of the character described comprising a hollow tube for the support of 30 the edge-roll, a hopper, means between the hopper and the supporting tube to feed the filling material to the latter, a feeding element operable in the tube, and means embracing the tube and the edge-roll to prevent 35 a lumpy packing of the latter during the filling of the edge-roll.

14. A device of the character described

comprising a hollow tube for the support of the edge-roll, a hopper, means between the hopper and the supporting tube to feed the filling material to the latter, a feeding element operable in the tube, and means whereby 40 embracing the tube and the edge-roll to prevent a lumpy packing of the latter during the filling of the edge-roll, and means whereby 45 said feeding means may be adjusted to regulate the tension upon the edge-roll during the operation of the device.

15. A device of the character described comprising a hollow tube, a hopper, means 50 between the hopper and supporting tube to feed the filling material to the latter, and a feeding element operable in the tube.

16. A device of the character described comprising a hollow corrugated tube, a hopper, means between the hopper and supporting tube to feed the filling material to the latter, a feeding element operable in the tube, and means coöperating with the tube and the edge-roll to prevent a lumpy packing of the 55 latter during the filling of the edge-roll.
